(57) **CLAIM**

The ornamental design for a process chamber manifold, as shown and described.

DESCRIPTION

FIG. 1 is a top, front, left side isometric view of a process chamber manifold, showing our new design.

FIG. 2 is a bottom, rear, right side isometric view thereof.

FIG. 3 is a left side elevation view thereof.

FIG. 4 is a right side elevation view thereof.

FIG. 5 is a front elevation view thereof.

FIG. 6 is a rear elevation view thereof.

FIG. 7 is a top plan view thereof.

FIG. 8 is a bottom plan view thereof.

FIG. 9 is a cross-sectional view taken along line 9-9 in FIG. 7; and,

FIG. 10 is a cross-sectional view taken along line 10-10 in FIG. 7.
